(57) **CLAIM**

The ornamental design for a tire, as shown and described.

DESCRIPTION

FIG. 1 is a perspective view of a tire, it being understood that the tread pattern of the tire repeats circumferentially throughout an outer circumference and shoulder of the tire, the opposite side perspective being identical thereto;

FIG. 2 is a front elevation view thereof;

FIG. 3 is a side elevation view of the right side thereof, the left side elevation being identical thereto; and,

FIG. 4 is a partially enlarged view of FIG. 2.

In the drawings, the broken lines depicting the sidewall, bead area and tire interior are for illustrative purpose only and form no part of the claimed design.

Broken lines in FIG. 2 are used for demarcation of enlarged portions of the tire and form no part of the claimed design.
